UNITED STATES PATENT OFFICE.

LEO PUNGS AND ROBERT HERZOG, OF BERLIN, GERMANY, ASSIGNEES TO C. LORENZ
AKTIENGESELLSCHAFT, OF BERLIN-TEMPELHOF, GERMANY.

HIGH-FREQUENCY TELEGRAPHING APPARATUS.

Application filed December 28, 1925, Serial No. 78,035, and in Germany February 13, 1925.

In telegraphing by means of high frequency oscillations it is oftentimes desirable for the generator producing the oscillations to keep the load uniform during keying.

5 This invention obtains this result for generators operating with intermediate circuits by connecting a resistance in parallel to the auxiliary magnetized choke coil or coils not located in the antenna circuit.

10 The single figure comprising the drawing is a diagram showing one specific application of our invention to an arc sending circuit.

In the figure G designates the generator, 15 for instance an arc generator, C_1 and C_2 are block condensers; C_3 and L_1 serve as tuning means; D_1 is the choke coil in the intermediate circuit, the high frequency coil of the choke being shunted by a resistance W . L_2 , 20 is the antenna tuning coil coupled to the intermediate circuit, the antenna tuning coil being connected to ground through the choke D_2 .

During the radiation of the oscillations 25 the chokes D_1 and D_2 are saturated, hence there is no choking effect when key T is closed. When the key is open, however, and when the chokes are not saturated, the antenna ceases to radiate due to the action of

30 the choke D_2 . Then the energy is conducted to the intermediate circuit choke D_1 to which

the resistance W is connected in parallel, a proper proportioning of said resistance furnishing a simple means coacting with said choke to regulate the performance of the 35 generator so as to obtain a uniform loading of same during the entire operation.

What we claim is:

1. In a high frequency signaling system, 40 the combination of a high frequency generator, a radiating antenna system, one or more intermediate circuits arranged between said generator and said radiating system, iron chokes placed in said radiating circuit and in a preceding intermediate circuit and 45 controlled simultaneously by one and the same controlling current, and a resistance connected in parallel with the choke located in said intermediate preceding circuit.

2. In a high frequency signaling system, 50 the combination of an arc oscillating circuit acting upon a radiating antenna circuit, iron chokes located respectively in said oscillating and said antenna circuit, both chokes having controlling windings controlled by 55 one and the same controlling current, and a resistance connected in parallel with said choke located in the arc oscillating circuit.

In testimony whereof we affix our signatures.

LEO PUNGS.
ROBERT HERZOG.
